UNITED STATES PATENT OFFICE.

JOHN C. VOGEL, OF PHILADELPHIA, PENNSYLVANIA.

GROUND-JOINT CLAMP.

1,053,684.

Specification of Letters Patent. Patented Feb. 18, 1913.

Application filed June 22, 1910. Serial No. 568,299.

To all whom it may concern:

Be it known that I, JOHN C. VOGEL, a citizen of the United States, residing in the city and county of Philadelphia, State of Pennsylvania, have invented a new and useful Ground-Joint Clamp, of which the following is a specification.

This invention relates to clamps for ground wire connections and has for an object to provide a connecting attachment whereby a ground wire can be quickly and conveniently secured to a gas or water pipe or equivalent device, whereby the electrical continuity between the wire and the pipe 15 shall be interrupted to the least possible degree.

In ground clamps as heretofore constructed, it has been found in practice that the parts are liable to become loose and form 20 a poor connection or else the parts corrode, whereby the conductivity thereof is materially lessened, while in many such devices the parts are tightened directly against the pipe or conduit, thereby injuring it.

25 In my present invention I have devised a clamping device simple in construction, efficient in operation and one which may be conveniently secured to a gas pipe, water pipe or other conduit without any previous 30 preparation and whereby a perfect electrical connection is maintained, regardless of the surrounding conditions.

It further consists of other novel features of construction, all as will be hereinafter 35 fully set forth.

For the purpose of illustrating my invention I have shown in the accompanying drawing one form thereof which is at present preferred by me, since the same has 40 been found in practice to give satisfactory and reliable results, although it is to be understood that the various instrumentalities of which my invention consists can be variously arranged and organized and that my 45 invention is not limited to the precise arrangement and organization of these instrumentalities as herein shown and described.

Figure 1 represents a perspective of a ground clamp embodying my invention in 50 position upon a pipe. Fig. 2 represents a sectional elevation of the same. Figs. 3 and 4 represent, respectively, perspectives of certain of the parts. Fig. 5 represents a sectional elevation of another embodiment of 55 my invention. Fig. 6 represents a perspec-

tive of one of the parts shown in Fig. 5. Fig. 7 represents a plan of Fig. 5.

Similar numerals of reference indicate corresponding parts in the figures.

Referring to the drawings: 1 designates a body portion or member, in the present instance substantially channel-shaped, having the top 2 and the sides 2*, the latter each being preferably provided with an opening or slot 3 adapted to receive a band 4, which is passed about a suitable support or conductor 5. The body portion 1 is also provided with an opening 6, preferably screw-threaded to receive a machine screw 7, or equivalent device, the same being utilized for the purpose of securing the ground wire 8 and other coöperating parts together. 9 designates a second body portion, holder or member, also preferably of channel form, having the sides 10 thereon. In the present instance the body portion 9 is sufficiently large to fit over the body portion 1 and telescope therewith under the action of the screw 7, it being noted that an aperture 11 is provided therein to permit the screw 7 to pass through and into engagement with the screw-threaded opening 6.

In the operation of the device the band 4 is passed through one of the openings 3 and its end bent into contact with the conductor 5, whereupon the body of the band 4 is brought through the other opening 3, as clearly shown in Fig. 2, thus gripping the bent end against the side of the conductor to prevent loosening or slipping of the band. 85 The ground wire 8 is now passed under the head of the screw 7 and the latter inserted into the openings 11 and 6, whereupon the two members may be drawn together, thus causing the band 4 to be drawn tightly 90 around the conductor 5 and the clamp firmly mounted in position.

Attention is directed to the fact that in this type of clamp the means for tightening the band 4 do not come into direct contact 100 with the conductor at any point and the entire tightening takes place through the telescoping of the two channel-members.

It will be noted that the novel construction herein disclosed makes it possible to 105 use bands of various lengths in order to adjust the same for substantially any size of pipe.

In the modification shown in Fig. 5, I have provided a body portion or holder 12 110

having slots 13 therein, suitably spaced apart in order to receive the sides 2^x of the member 1, on which the holder 12 is fitted. The screw 7, during the tightening action, 5 directly engages the holder 12 and forces the same down to bind the band passing through the openings 3.

In Fig. 5 I have shown one end of the band passing through both openings 3 and 10 of course it will be understood that there are various ways in which the band and clamp may be interlocked for the end desired.

It will now be apparent that I have devised a complete, unitary structure, whereby an efficient electrical connection may be made between a suitable surface and the band and the clamp may be readily attached without taking the same apart and 20 that the parts are few and inexpensive.

It will now be apparent that I have devised a novel and useful construction which embodies the features of advantage enumerated as desirable in the statement of the 25 invention and the above description and while I have in the present instance shown and described the preferred embodiment thereof which has been found in practice to give satisfactory and reliable results, it 30 is to be understood that the same is susceptible of modification in various particulars without departing from the spirit or scope of the invention or sacrificing any of its advantages.

35 Having thus described my invention, what I claim as new and desire to secure by Letters Patent, is:

1. In a device of the character stated, a member, a second member entirely inclosed 40 by said first member and having an opening in each side thereof, a band adapted to encircle a suitable conductor and pass through said openings, and means coöperating with said members to tighten said band around 45 said pipe, said means serving to move said second member partially outside of said first member whereby said band may be placed in operative position.

2. In a device of the character stated, two

interfitting body portions, a flexible band 50 connected with a suitable part thereof, and means to move one of said body portions entirely within the other for tightening the band around a suitable support, said means serving to move said body portion partially 55 outside of said outer body portion, whereby said band may be placed in operative position.

3. In a device of the character stated, two body portions, each having top and side 60 plates suitably spaced apart, one of said body portions being adapted to fit entirely within the other and be inclosed thereby, a band connected with a suitable part of said body portions, and means actuating said 65 body portions for tightening the band around a suitable support.

4. In a device of the character stated, a channel member having an opening therein, a second channel member telescopically arranged with respect to said first channel member and having a slot in each side thereof and a screw threaded opening, a band adapted to encircle a suitable conductor and pass through said slots and a 75 binding screw passing through said members and adapted to draw one of said members entirely within the other whereby said band is tightened around said conductor, said screw serving to move said second channel 80 member partially outside of said first channel member, whereby said band may be placed in operative position.

5. In a device of the character stated, an outer member, an inner apertured member 85 of substantially channel shape adapted to move entirely within said outer member, a band adapted to encircle a suitable conductor and pass through said apertured member, and means for supporting said inner 90 member partially outside of said outer member and for tightening said band about said conductor.

JOHN C. VOGEL.
